UNITED STATES PATENT OFFICE

2,690,273

ELEVATED STORAGE TANK

Christian Arne, Chicago, Ill., assignor to Chicago
Bridge & Iron Company, a corporation of Illinois

Application April 11, 1949, Serial No. 86,615

2 Claims. (Cl. 220—1)

1

This invention relates to column construction and more particularly to an air filled structural member having increased compressive strength.

In the construction of elevated structures supporting members are used which are under compressive forces. The normal practice has been to design the supporting members so as to have sufficient strength safely to support the structure. When this principle is applied to an elevated structure supported by steel columns the thickness of the steel in each column is so calculated as to produce such a supporting member. Obviously, as the weight of the structure to be supported increases, the amount of steel used to support the structure also increases. It is clear that any saving in the amount of steel necessary to support an elevated structure reduces the cost, not only because of the smaller quantity of steel used but because of the fact that lighter columns are easier to manufacture, assemble, and weld.

I have found that by filling a hollow supporting member with compressed fluid, for example with compressed air, that I can increase substantially the compressive load which such a column can withstand.

The invention will be described in conjunction with the accompanying drawings in which:

Fig. 1 is a sectional view through a column embodying the invention;

Fig. 2 is a sectional view through a supporting column embodying the invention and made up of a plurality of sections;

Fig. 3 is a vertical section through an elevated water tank supported by a column constructed in accordance with the invention.

Referring now to the drawings I show in Fig. 1 a column 10 having a cylindrical sidewall 11 resting upon a base plate 12 which in turn rests upon a foundation 13. The upper end of the column is closed by a plate 14 and each of the plates 12 and 14 is welded to the column, as shown.

If the radius of the column 10 is R and the thickness of the shell 11 is t and if the allowable compression stress in the column is C, the load W the column can carry equals $2\pi R t C$.

If the ends of the column are closed and the allowable circumferential tensile stress is T, the column can withstand an internal fluid pressure of P and

$$P = \frac{tT}{R}$$

The cross-sectional area of the column is, of course, πR^2 and, therefore, the fluid pressure P increases the carrying capacity of the column by w, and

$$w = \frac{tT}{R} \pi R^2 = tT \pi R$$

5

It is clear from the last equation that the increase in the carrying capacity w is independent of the column length and of W.

It, therefore, follows that:

$$\frac{w}{W} = \frac{tT \pi R}{2\pi R t C} = \frac{T}{2C}$$

therefore,

$$w = W \frac{T}{2C}$$

While with certain columns the allowable compression C may be more than the allowable tension T, it is the general rule that T is at least equal to C and is usually greater. Thus, for example, if the allowable tension T is 15,000 lbs. per sq. inch and the allowable compression C is also 15,000 lbs. per sq. inch,

20

$$\frac{T}{2C} = .5$$

and, therefore, $w = .5W$. Thus, the carrying capacity of the column is increased by 50%.

Failure in diagonal shear is quite unlikely since 25 structural plates are known to have a tensile strength of about 60,000 p. s. i. and a shear strength of 40,000 p. s. i. Thus considering a 1 inch square of the column wall, t inches thick with C p. s. i. compressive stress and T p. s. i. tensile stress acting on the square, the shearing stress on a diagonal section is

$$\frac{.707Ct + .707Tt}{1.414t}$$

35 If $C = T$ p. s. i., then shearing stress on the diagonal is equal to T. Working stresses for C and T are known to be 15,000 p. s. i. which is far below the 40,000 p. s. i. shear strength.

It will also be clear to those skilled in the art 40 that the fluid to be placed under pressure in a tubular supporting column need not be a gas but may be a liquid. For example, tubular compression members may be filled with water under pressure and immersed in water. Such supporting members may be, for example, sub-surface supports for a bridge and being located under the surface of the water are not subject to bending from the weight of the water contained therein.

50 Naturally, with an increase in the carrying capacity of the column the thickness of the steel required safely to support any load may be reduced.

The column may be charged with fluid under 55 pressure, such as compressed air, by means of a pump or otherwise through a valve device which is sealed up after the proper pressure has been reached. The pressure within the column can

also be attained by placing therein a volatile liquid having a vapor pressure which will result in the desired pressure at the prevailing temperatures. A column constructed in accordance with this invention should be inspected for pressure about as often as it is painted.

Compressed air inside of the column tends to keep the column round and takes the place of stiffening rings and obviously with greater stiffness it is reasonable to allow greater compressive stress in the steel column. Thus, the value of C may be increased.

Referring now to the column shown in Fig. 2, it can be seen that it is made up of a first tubular section 15 and a second tubular section 16. The lower end of the section 15 is sealed to a plate 17 which rests upon a foundation 18 while the upper end of section 16 is sealed by another plate 19 welded thereto. Each of the sections 15 and 16 is sealed adjacent the end opposite the plates by diaphragms 20 and 21 respectively. It will be noted that that portion of each section between the plates 17 or 19 and the diaphragm 20 or 21 is constructed of metal thinner than the metal employed between the diaphragm and the adjoining ends of the section. It is contemplated that the closed portion of each section, that is, the portion between the end plate and the diaphragm will be filled with a compressed gas to create therein a circumferential tension which at the highest temperatures to be expected in the area where the column is to be used are substantially equal to the allowable circumferential tension stress. Inasmuch as that portion of each section adjacent their abutting ends is not reinforced by compressed air those sections are made thicker and may be welded to each other by welding in the groove 22.

Fig. 2 demonstrates clearly the savings effected by the use of my invention in any particular column construction. Were it not for the fact that each section is filled (and thus reinforced) with compressed air between the plates and the diaphragms, the whole of each of such sections would have to be constructed of steel as thick as is required at the abutting ends of those sections as shown in the drawings.

Referring now to Fig. 3, I show a specific structure, namely an elevated water tank, embodying the column construction of the invention. In that figure a substantially spherical tank 30 is supported on a closed cylindrical column 31. The lower edge of the column is welded or otherwise sealed to a base plate 32 which rests upon a foundation 33 while the upper edge of the column 31 is welded to the tank 30. A riser 34 extends downwardly from the tank through the column and thence outwardly through the foundation, the riser being sealed to the base plate 32 as by the weld 35. A hollow pipe 36 is secured to the bottom of the tank 30 and extends upwardly therethrough, the pipe opening at its upper end to the interior of the tank 30 above the liquid level therein and opening at its lower end to the interior of the column 31.

When the tank 30 is first filled with water the air therein is compressed and forced through the pipe 36 into the interior of the column 31 to increase the air pressure therein and thus to add to the permissible compressive stress on the column. Should the volume of the column be such, relative to the volume of the tank, that the filling of the tank does not sufficiently increase the pressure within the column, additional air under pressure may be admitted through the fitting 37.

As water is withdrawn from the tank and

liquid level falls therein, air within the column 31 will enter the space above the falling liquid level and thus reduce the pressure in the column. However, as the weight of the tank 30 decreases 5 when water is withdrawn therefrom it is clear that the load to which the column is subjected is also reduced. On the other hand, when the tank is being refilled and its weight is increasing the compression of the air within the column 31 also increases.

An additional feature of the elevated tank shown in Fig. 3 is that the water pressure at the bottom of the riser is equal to the hydrostatic head of the water above the outlet plus the pressure of air existing in the space above the liquid level in the tank. Thus, the compressed air within the column 31 serves not only to strengthen and reinforce that column but also to increase the water pressure at the outlet.

By the use of the word "columns" in the specification and claims I do not restrict myself, nor are the invention and the principles thereof restricted to vertical, cylindrical, or metallic columns. It is clear that the invention is equally applicable to a strut and truss bridge, or to an arch, or to any other supporting member subjected to compression stresses.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. An elevated liquid storage tank supported by a single hollow column filled with gas under superatmospheric pressure and a pipe connecting the interior of the column with the interior of the tank above the level of the liquid.

2. An elevated liquid storage tank comprising, a storage portion, a hollow metal column supporting the storage portion at a fixed elevation above a base, said column alone being incapable of supporting the storage portion when full, said hollow column being filled with gas under pressure to raise its supporting strength and a connection providing communication between the interior of the column and the interior of the tank above the level of the liquid.
